UNITED STATES PATENT OFFICE

WILLIAM PARKER, OF DUNBAR, WEST VIRGINIA.

HAIR-PIN.

1,179,452

Specification of Letters Patent. Patented Apr. 18, 1916.

Application filed June 22, 1914. Serial No. 846,667.

To all whom it may concern:

Be it known that I, WILLIAM PARKER, citizen of the United States, residing at Dunbar, in the county of Kanawha and State of West Virginia, have invented certain new and useful Improvements in Hair-Pins, of which the following is a specification.

This invention relates to hairpins, and more particularly to that type embodying movable arms held normally crossed, or in contact with each other, by means of a spring, the same being provided with handles whereby to spread said arms.

The object of my invention is to provide a hairpin which is readily insertible in the hair by spreading the spring pressed arms and after the same has been placed in the hair releasing the said arms whereby to clamp the hair and prevent accidental displacement therefrom.

Other objects will become apparent as a more thorough understanding of my invention is attained.

The invention consists in the construction and arrangement of the several parts which will be more fully described and claimed.

In the drawings:—Figure 1 is a perspective view of a hairpin embodying the preferred form of my invention. Fig. 2 is a side elevation of the same. Fig. 3 is an end elevation of the same. Fig. 4 is a modified form of my invention showing the spring arms in crossed relation.

Referring more particularly to the drawing in the preferred form of my invention, I provide a hairpin formed of a single strand of wire and consisting, particularly, of two spring clamping arms 1 and 2, a spring 3 formed therewith and interposed therebetween, and operating handles 4 and 5 integrally formed upon the same, whereby the contraction of the said handles 4 and 5 will expand the spring pressed arms 1 and 2 against the action of the spring 3 facilitating the insertion of the hairpin into the hair.

In the manufacture of this device, the wire strand is coiled at its intermediate portion to provide the spring 3 heretofore mentioned, the free ends of the said strand of wire being twisted upon themselves at points 6 and 7, whereby to provide the aforesaid handles 4 and 5 and extend downwardly to provide the clamping arms 1 and 2 heretofore referred to.

As will be plainly seen in Fig. 2, the portions 8 and 9 of the spring arms 1 and 2 are received within the convolutions of the spring 3, thereby providing a bearing or fulcrum for said arms and facilitating the movement of the same.

The arms 1 and 2 are twisted at the points 6 and 7 in such a manner as to provide contacting portions 10 and 11, said portions 10 and 11 being adapted to contact when pressure is applied on the handles 4 and 5, thereby limiting the movement inwardly of the said handles 4 and 5. This feature is shown in dotted lines at the point 12. The said clamping arms 1 and 2 are offset toward one another as shown at 13 and 14 to cause the same to contact at the point 15, thereby insuring the securement in the hair.

The arms 1 and 2, as shown in the modified form of my invention in Fig. 4, are adapted to cross intermediate their ends as shown at the point 16, the said arms being offset at 17 and 18 in the same manner as shown in Figs. 1 and 2 at the points 13 and 14, thus providing a means to prevent the accidental displacement of the hairpin from the hair. It will be understood that when the arms 1 and 2 are crossed, as shown in Fig. 4, the hair is gripped between the said arms and assists the offset portions 17 and 18 in holding the hairpin in the hair.

The operation it is thought will be clearly understood from the drawings and description. When it is wished to insert the hairpin in the hair, the handles 4 and 5 are gripped between the forefinger and the thumb, pressure applied to the same, whereupon the arms 1 and 2 will spread. Holding the hairpin in this position the same is inserted in the hair and the handles 4 and 5 released. This allows the arms 1 and 2 to come together and clamp the hair between them.

In Fig. 4 the same function is performed, the difference being that the arms 1 and 2 cross, thereby serving as an additional means to prevent displacement of the hairpin from the hair. The function of the portions 10 and 11 it is thought is clearly understood, and if undue pressure is applied to the handles 4 and 5, the portions 10 and 11 will contact thereby limiting the movement of the handles 4 and 5 toward one another. The construction of the device, whereby the portions 8 and 9 are adapted to seat within the convolutions of the

spring 3, provides a bearing means or a fulcrum, and also gives greater strength to the device.

While I have shown and described a specific form of my invention, the right is reserved to change any of the parts thereof which shall be within the scope of the appended claims.

Having thus described my invention what I claim and desire to secure by Letters Patent is:—

1. A hair pin formed of a single strand of wire, provided intermediate its ends with a coil spring, said strand of wire being looped and twisted adjacent said coil spring to provide handles disposed relatively substantially parallel to the axis of the spring, and operative between the convolutions thereof, said strand of wire having its free ends disposed substantially in parallelism to provide gripping arms.

2. A hairpin made from a single strand of wire, coiled at its intermediate portion to provide a spring, clamping arms integral therewith and normally held in clamping relation by said spring, said arms being twisted and looped upon themselves adjacent the spring portion to provide operating handles, the twisted portions of said arms

being adapted to seat within the convolutions of the spring to afford fulcrums, and means formed with the said twisted and looped portions whereby to limit the movement of the said handles toward one another.

3. A hair pin formed of a single strand of wire provided intermediate its ends with a convolute spring, said strand being looped and twisted adjacent the said convolute spring to provide handles, the portions of said strand of wire affording handles being so bent that contact means is afforded on each handle to limit the movement together of the same.

4. A hair pin formed of a single strand of wire provided intermediate its ends with an integrally formed spring, handles formed therewith by looping and twisting the said strand of wire adjacent the coil spring, portions of said handles being engageable in the convolutions of the coil spring to provide bearing surfaces.

In testimony whereof I affix my signature in presence of two witnesses.

WILLIAM PARKER.
